CLAIM

The ornamental design for a wafer basket, as shown and described.

DESCRIPTION

FIG. 1 is a front elevational view of a wafer basket showing our new design;

FIG. 2 is a top plan view thereof;

FIG. 3 is a left side elevational view thereof, the right side elevational view being a mirror image thereof;

FIG. 4 is a bottom plan view thereof;

FIG. 5 is a rear elevational view thereof; and,

FIG. 6 is a sectional elevational view thereof; taken along line 6—6 of FIG. 3.

FIG. 2**FIG. 3****FIG. 1****FIG. 4****FIG. 6****FIG. 5**
